GARMENT HANGER

John Hiebert, Brownvale, Alberta, Canada

Application August 7, 1946, Serial No. 689,059
In Canada July 23, 1945Section 1, Public Law 690, August 8, 1946
Patent expires July 23, 1965

3 Claims. (Cl. 223—89)

1

My invention relates to garment hangers, more particularly having reference to a device for such purposes capable of being folded for storage in a comparatively small space.

In the art to which the invention relates various forms of folding garment hangers have been proposed in which the hanger is made to fold to reduce it to a more compact form for storage or like purposes.

The present invention contemplates improvements in hangers of this character by provision of a device capable of folding in a manner to form a roll that may be contained in a relatively small space.

One of the objects of the invention is accordingly to provide a garment hanger adapted to be folded into a relatively small space.

A further object of the invention is to provide a hanger of this character that while capable of folding or rolling into a relatively small space, yet provides a strong support for garments to be hung on it.

A still further object of the invention is to provide in a garment hanger brace means for the hanger for use where extra strength may be required.

A still further object of the invention is to provide an improved hook for the hanger, including cushioning means for the hook.

Other features and advantages of the invention will become apparent by reference to the accompanying description taken in conjunction with the drawings wherein like characters of reference indicate like parts throughout the several views and wherein:

Fig. 1 is a side elevation of the garment hanger assembled.

Fig. 2 is a detail side view of a link for suspension of the body of the hanger.

Fig. 3 is a side edge view of the brace member taken by itself.

Fig. 4 is a top plan view of a section of the body of the hanger.

Fig. 5 is a detail view showing the interlocking of the links at the center of the hanger.

Having reference to the drawings the hanger body 18 is made up of a series of connected links interlocked in a manner to give mutual support in one direction and to fold or roll in the other.

Each link of the hanger is made up of a piece of material bent to provide converging leg portions 2 and 3 with connecting section 1, the legs terminating at the ends in hooks 4. The hooks on the legs of each link are engageable with the connecting section of the next but one link in a series

and the legs of each link bear against the connecting portion of the link intervening between the hooks and connecting portion. This arrangement will be more readily apparent by reference to Figure 4.

To form the body of the hanger two sets of connected links 16 and 17 are preferably used, with one set reversed in relation to the other. This leaves a connecting section 1 of each set of links 10 outward.

The two sets of links interlock at the center, this being illustrated in detail in Figure 5 in which the inner links on each set cross to engage the connecting section 1 of the next but one link of the opposing set, the end hooks being indicated by the numeral 9, of Figure 5, one set of the legs of an end link being positioned between the legs of the opposing link of the opposite set, the hooks 9 being the hooks of the legs that cross.

For suspension of the connected sets of links a hanging bracket is provided comprising a pair of hook members 8 engaging the hooked ends of links and in turn engaged by a lower horizontal portion 10 of a triangle 11. The triangle has a suspension hook consisting of a shank portion 12 with hook member 13. On the shank 12 are stops 14 spaced apart one above and one below the connection with the triangle, this connection being obtained by provision of a suitable opening in the upper angle of the triangle in which the shank 12 is freely slid able. On the shank 12 is a spring 15 between the lower stop 14 and the top of the triangle.

For bracing the body of the hanger where extra weight is to be put on it a brace section 19 is provided, separately illustrated in Figure 3. In this the links at each end are engaged by hooks each providing a shank 5 with hook portion 6 engaging a connection 1 of a link and a further hook 7 for engagement of a connecting portion of a link in the body of the hanger, the brace being disposed to resist downward pressure on the body of the hanger as when a garment is carried on the hanger.

The links for the hanger are made of steel, necessarily sufficiently strong so as not to bend or give under weight of the garment carried by the hanger.

In the use of the hanger the parts are assembled as illustrated in Figure 1, with or without the brace section. When folded for putting away out of use the sets of links forming the body of the hanger may be rolled, as for example in Figure 1 the rolling of the body would be up, this being the direction in which the links fold. Similarly

the brace section may be rolled, and the whole assembly when so rolled may be put in a comparatively small space.

While I have herein disclosed a preferred embodiment of my garment hanger, it is obvious that changes may be made in the formation of parts within the spirit and scope of the invention as defined in the appended claims, and such changes would be considered as a part of the invention as herein disclosed.

What I claim and wish to secure by Letters Patent is:

1. In a garment hanger, a body portion over which the garment is to be placed, said body portion comprising a series of connected links, each of said links consisting of a single piece of material bent to provide a center portion and opposing converging legs, said legs terminating in hooks, said links being connected with the hooks of each link engaging the center portion of the next but one link in the series. 15

2. A garment hanger comprising a body on which the garment is to be hung, a suspension hook, means attaching said hook to the body, and a brace for the body, said brace including hooks detachably engageable with the body, and said body and brace being each formed of a series of links, each of said links comprising a single piece 25

of material bent to provide a straight center portion and two leg portions extending in opposing converging relationship, said legs terminating in hooks and said links being connected with the hooks of each link engaging the center portion of the next but one succeeding link in the series.

3. A device as defined in claim 2 in which the means for attachment of the suspension hook includes two hook members, and the body of the hanger is formed of two separate sets of connected links, the one set being reversed in relation to the other and the inner terminating hooks on each set engaged with the hook members of the suspension hook.

JOHN HIEBERT.
